HAND BRAKE MECHANISM

Edward W. Zane, Chicago, Ill., assignor to Union Railway Equipment Co., Chicago, Ill., a corporation of South Dakota

Application August 25, 1938, Serial No. 226,665

13 Claims. (Cl. 188—81.1)

My invention relates to hand brakes for railway cars and more particularly to the operating or control mechanism therefor.

In those types of hand brakes wherein suitable gearing is interposed between the hand wheel and the brake chain to provide the required leverage for setting the brakes, it is customary to incorporate a ratchet-pawl mechanism which is automatically engaged when the hand wheel is rotated in a brake setting direction to hold the brake shoes in any determined position. Some provision is further made to secure the release of the pawl when desired. In general, only a single pawl is employed which not only unbalances the load application on the ratchet, but is also subject to the further objection that, in the event of breakage of the pawl, the mechanism is thrown out of service.

It is therefore one object of my invention to provide a hand brake mechanism having two pawls which are disposed to substantially equalize the load on the ratchet during the application of the brakes and which are moved simultaneously into and out of engagement with the ratchet.

A further object is to devise a hand brake mechanism of the character indicated in which the two pawls are automatically released by a gravity movement of the actuating handle, thereby enabling the operator to apply both hands to the hand wheel.

These and further objects of my invention will be set forth in the following specification, reference being had to the accompanying drawings, and the novel means by which said objects are effectuated will be definitely pointed out in the claims.

In the drawings:

Figure 1 is an elevation of my improved mechanism taken along the line 1—1 in Fig. 2, looking in the direction of the arrows;

Figs. 2 and 3 are sections along the lines 2—2 and 3—3 in Fig. 1, looking in the direction of the arrows;

Fig. 4 is a fragmentary elevation of the device as it appears in position on a railway car, looking in the direction of the arrow 4 in Fig. 3;

Figs. 5 and 6 are sections along the line 5—5 in Fig. 2, looking in the direction of the arrows, showing, respectively, the engaged and released positions of the pawls.

Referring to the drawings, the numeral 10 designates the usual brake chain, one end of which extends beneath the body of the car in the customary manner for affixation to the braking

system (not shown) while the other terminal link is connected to a pin 11 that is mounted in and extends laterally from a spoke of a spur gear 12. The gear is journaled on a shaft 13 whose ends are supported by the opposite walls of an enclosing housing 14 having a plurality of lugs 15 through which suitable bolts extend for securing the housing to the end wall of the car body 16. The housing prevents impairment of the operation of the mechanism by ice, sleet and snow, or foreign matter such as coal, stones, etc. Also freely journaled on the shaft 13 beside the gear 12 is a reeling roller 17 that may have its peripheral surface appropriately grooved to receive alternate lengths of the brake chain during the winding operation, as hereinafter described.

The gear 12 meshes with a pinion 18 that may be integrally formed with an operating shaft 19 whose rear end is journaled in the rear wall of the housing 14 and whose intermediate portion is 20 journaled in a plate 20 that is supported from a plurality of ears 21 adjacent the front side of the housing 14. The front end of the shaft 19 extends through an opening in a cover plate 22 and has affixed on the end thereof a hand wheel 23 that is of the so-called vertical type. However, it will be understood that the mechanism which forms the subject matter of my invention is not restricted to use with vertical hand wheels, but also may be employed in connection with those of the horizontal type.

Also integrally formed with the operating shaft 19 is a ratchet wheel 24 and a pair of pawls 25 and 26 are symmetrically disposed with respect to the ratchet wheel so as to engage with the 35 teeth thereof at opposite sides of the wheel, or substantially at the ends of any diameter thereof. By this provision, it is possible to equalize or balance the load application on the ratchet. The pawl 25 is of the tension type, while the pawl 26 40 is of the compression variety and may be integrally formed as a part of a shaft 27 whose ends are journaled in the rear wall of the housing 14 and in the plate 20, respectively (see Fig. 3). The pawl 26 is provided with a bifurcated arm 45 28 that extends toward the pawl 25 which in turn is provided with a tooth 29 that is cooperatively related to the arm 28 so that when the pawl 25 is operated as hereinafter described like movements will be imparted to the pawl 26.

The pawl 25 is provided with a hub 30 that is freely journaled on a shaft 31 whose ends are carried by the rear wall of the housing 14 and the plate 20, respectively, the front end of the shaft extending through the cover plate 22 for its 55

securement to a release actuating handle 32. The pawl hub 30 is provided rearwardly with a sector lug 33 whose ends form rotarily spaced abutments 34 and 35. A similar sector lug 36 may be integrally formed with the shaft 31 and the ends thereof form rotarily spaced abutments 37 and 38. The sector lugs 33 and 36 are positioned in the same plane of rotation and when the pawls are engaged and the handle is in the position shown in Fig. 4, the abutments 34 and 37 are in contact, while the abutments 35 and 38 are spaced apart. This condition is illustrated in Figs. 1 and 5. A stop nose 39 may also be integrally formed on the shaft 31 in axially spaced relation to the sector lugs and this nose is intended to engage with a shoulder 40 on the housing 14 to limit the releasing movement of the handle 32 as hereinafter described.

In Fig. 1, the pawls are shown engaged with the ratchet wheel 24, with the release handle 32 occupying the position shown in Fig. 4, but no tension has been applied to the brake chain 19. To set the brakes, the operator rotates the hand wheel 23 in a clockwise direction, as viewed in Fig. 1, and during this operation the pawls 25 and 26 merely slip over the teeth of the ratchet in the customary manner. When the required tension has been established in the brake chain 19, the pawls are fully engaged with the ratchet wheel and thus maintain the established setting of the brakes. The relation of the pawls and the ratchet wheel is then substantially as illustrated in Fig. 1 and particular attention is directed to the balancing of the load on the ratchet wheel which provides a better stress distribution in the ratchet wheel in comparison with previous devices employing single pawls.

When it is desired to release the brakes, the operator first moves the release handle 32 from the position shown in Fig. 4 to that indicated by the numeral 41 in Fig. 6. This movement of the handle may be accomplished freely until the abutment 38 contacts the abutment 35 when further movement of the handle in the indicated direction is resisted by the friction between the pawls and the teeth of the ratchet wheels. At this juncture, it will be noted from an examination of Fig. 6 that the release handle occupies a position above and to the right of the axis of the shaft 31. The operator then slightly rotates the hand wheel 23 in a winding or clockwise direction sufficiently to relieve the friction between the teeth of the ratchet and the pawl, this position of the ratchet being generally indicated by dotted lines in Fig. 6. The pawls being thus freed for movement, are shifted to the positions indicated by dotted lines in Fig. 6 by the gravity movement of the release handle 32 which assumes the position designated by the numeral 42 and one in which further movement in a releasing direction is limited by engagement of the nose 39 with the shoulder 40. The toothed or interconnected relation between the pawls 25 and 26 insures that both of the pawls will be simultaneously moved to release position. As soon as the handle has moved the small angular distance indicated in Fig. 6, as can be observed by the operator, it is merely necessary for his grip to be released from the hand wheel to permit the same to spin in the usual manner and relieve the brakes.

As already stated, the fully released position of the pawls is indicated by the numeral 42 in Fig. 6. At this time, the abutments 35 and 38 are in contact, while the abutments 34 and 37

are spaced from each other. To again place the pawls in engagement with the ratchet wheel, the release handle is moved from the position represented by the numeral 42 in Fig. 6 to that shown in Fig. 4, being the same as that indicated by the numeral 43 in Fig. 6, and, during this movement, the pawls automatically engage the ratchet due to the fact that they are hung for self-ratcheting action. The handle 32 when in the position shown in Fig. 4 assists in maintaining the pawls in ratcheting engagement, while the contacting of the abutments 34 and 37 serves to limit further movement of the handle in the indicated direction.

The use of the twin pawls contributes to the safety characteristics of the device, as does the fact that when setting and relieving the brakes, the operator may keep both hands firmly gripped on the hand wheel 23 and need not have his attention distracted by the necessity for handling other portions of the apparatus.

I claim:

1. Hand brake mechanism comprising in combination, a rotatable ratchet adapted for connection to a winding device, a pair of pivoted and interconnected pawls operatively related to the ratchet, and actuating means freely rockable in one direction to contact one pawl and thereby engage both pawls with the ratchet and in the opposite direction to contact said one pawl when further movement of the actuating means is resisted by friction between the pawls and ratchet teeth, the actuating means having a weighted portion causing further rotation thereof in said opposite direction under the action of gravity to release the pawls when said friction is relieved by a rotation of the ratchet in a winding direction.

2. Hand brake mechanism comprising in combination, a rotatable ratchet adapted for connection to a winding device, a pair of pivoted and interconnected pawls operatively related to the ratchet, and actuating means freely rockable between a limiting position in which the pawls are engaged with the ratchet and a temporary limiting position in which movement of the means is resisted by friction between the pawls and ratchet teeth, the actuating means having a weighted portion causing further rotation thereof in said resisted direction under the action of gravity to release the pawls when said friction is relieved by a rotation of the ratchet in a winding direction.

3. Hand brake mechanism comprising in combination, a rotatable ratchet adapted for connection to a winding device, a pair of pivoted and interconnected pawls operatively related to the ratchet and hung for self-ratcheting action, one of the pawls having a first pair of rotarily spaced abutments, and rockable pawl actuating means having a second pair of rotarily spaced abutments located in the plane of rotation of the first abutments, the actuating means being freely rockable in one direction to permit the pawls to engage the ratchet and to contact an abutment thereof with a pawl abutment to limit movement of the actuating means, and in the opposite direction to contact the other abutments when further movement of the actuating means is resisted by friction between the pawls and ratchet teeth, the actuating means having a weighted portion causing further rotation thereof in said opposite direction under the action of gravity to release the pawls when the friction is relieved by a rotation of the ratchet in a winding direction.

4. Hand brake mechanism comprising in combination, a rotatable ratchet adapted for connection to a winding device, a rock shaft, a pair of pivoted and interconnected pawls operatively related to the ratchet and hung for self-ratcheting action, one of the pawls being freely rotatable on the shaft and having a first pair of rotarily spaced abutments, a second pair of rotarily spaced abutments provided on the shaft and located in the plane of rotation of the first abutments, and an actuating handle secured to the shaft, the handle being freely rockable in one direction to permit the pawls to engage the ratchet and to contact a shaft abutment with a pawl abutment to limit movement of the handle and in the opposite direction to contact the other abutments when further movement of the handle is resisted by friction between the pawls and ratchet teeth, the handle in said last-named position being adapted for further movement under the action of gravity to release the pawls when the friction is relieved by a rotation of the ratchet in a winding direction.

5. Hand brake mechanism comprising in combination, a rotatable ratchet adapted for connection to a winding device, a pair of pivoted and interconnected pawls located to engage the ratchet approximately at opposite ends of a diameter thereof to substantially balance the load on the ratchet and hung for self-ratcheting action, one of the pawls having a first pair of rotarily spaced abutments, and rockable pawl actuating means having a second pair of rotarily spaced abutments located in the plane of rotation of the first abutments, the actuating means being freely rockable in one direction to permit the pawls to engage the ratchet and to contact an abutment thereof with a pawl abutment and in the opposite direction to contact the other abutments when further movement of the actuating means is resisted by friction between the pawls and ratchet teeth, the actuating means having a weighted portion causing further rotation thereof in said opposite direction under the action of gravity to release the pawls when the friction is relieved by a rotation of the ratchet in a winding direction.

6. Hand brake mechanism comprising in combination, a rotatable ratchet adapted for connection to a winding device, a pivoted tension pawl and a pivoted compression pawl engageable with the ratchet to prevent unwinding of the device and having toothed engagement with each other to interconnect the same, and means connected to one of the pawls for simultaneously moving the pawls into and out of engagement with the ratchet to respectively prevent and permit release of the device.

7. Hand brake mechanism comprising in combination, a rotatable ratchet adapted for connection to a winding device, a pivoted tension pawl and a pivoted compression pawl located to engage the ratchet approximately at opposite ends of a diameter thereof to substantially balance the load on the ratchet and having toothed

engagement with each other to interconnect the same, and means connected to one of the pawls for simultaneously moving the pawls into and out of engagement with the ratchet to respectively prevent and permit release of the device.

8. Hand brake mechanism comprising in combination a rotatable ratchet adapted for connection to a braking device, a tension pawl, a compression pawl, and means for simultaneously moving the pawls into and out of engagement with the ratchet to respectively prevent and permit release of the device.

9. Hand brake mechanism comprising in combination, a rotatable ratchet adapted for connection to a braking device, a tension pawl, a compression pawl, the pawls being connected for simultaneous movement, and means connected to one of the pawls for simultaneously moving the pawls into and out of engagement with the ratchet to respectively prevent and permit release of the device.

10. Hand brake mechanism comprising in combination, a rotatable ratchet adapted for connection to a braking device, a tension pawl and a compression pawl located to engage the ratchet approximately at opposite ends of a diameter thereof to substantially balance the load on the ratchet, and means for simultaneously moving the pawls into and out of engagement with the ratchet to respectively prevent and permit release of the device.

11. Hand brake mechanism comprising in combination, a rotatable ratchet adapted for connection to a braking device, a tension pawl and a compression pawl located to engage the ratchet approximately at opposite ends of a diameter thereof to substantially balance the load on the ratchet, the pawls being connected for simultaneous movement, and means connected to one of the pawls for simultaneously moving the pawls into and out of engagement with the ratchet to respectively prevent and permit release of the device.

12. Hand brake mechanism comprising in combination, a rotatable ratchet adapted for connection to a braking device, a tension pawl and a compression pawl located on the same side of the ratchet axis and having cooperating integral formations whereby movements of one pawl into and out of engagement with the ratchet effects like movements of the other pawl, and means for actuating one of the pawls.

13. Hand brake mechanism comprising in combination, a rotatable ratchet adapted for connection to a braking device, a tension pawl and a compression pawl located on the same side of the ratchet axis and hung for self-ratcheting action, the pawls having cooperating integral formations whereby movements of one pawl into and out of engagement with the ratchet effects like movements of the other pawl, and means for actuating one of the pawls.

EDWARD W. ZANE.
